AIR DISCHARGE DRYER TUNNEL

Dean C. Rupp, Burnsville, Minn., assignor to Rupp Industries, Inc., Bloomington, Minn., and Passpoint Corporation, Maryland Heights, Mo., fractional part interest to each

Filed Feb. 1, 1972, Ser. No. 222,724

Term of patent 14 years

Int. Cl. D15—05

U.S. Cl. D49—12

FIG. 1

FIG. 2

FIG. 4

FIG. 4

FIG. 5

FIG. 1 is a perspective view of the air discharge dryer tunnel showing the new design;

FIG. 2 is a side elevational view of the air discharge dryer tunnel showing the side opposite the side shown in FIG. 1;

FIG. 3 is a cross sectional view taken along the line 3-3 of FIG. 5 showing an inside wall of the air discharge dryer tunnel, the opposite inside wall is a mirror image of FIG. 3;

FIG. 4 is a bottom plan view thereof; and
FIG. 5 is a top plan view thereof.

I claim:

The ornamental design for the air discharge dryer tunnel, substantially as shown and described.
